UNITED STATES PATENT OFFICE.

WILLIAM F. MAAS, OF ROCHESTER, NEW YORK, ASSIGNOR TO WOOD SPECIALTIES, INC., OF ROCHESTER, NEW YORK, A CORPORATION OF NEW YORK.

DESIGN FOR A TOY.

• 55,427.

Specification for Design.

Patented June 8, 1920.

Application filed March 6, 1920. Serial No. 363,830. Term of patent 14 years.

To all whom it may concern:

Be it known that I, WILLIAM F. MAAS, a citizen of the United States, residing at Rochester, in the county of Monroe and State of New York, have invented a new, original, and ornamental Design for Toys, of which the following is a specification, and of which the accompanying drawing is a representation.

In the drawing:

The figure is a perspective view of my new design.

I claim:

The ornamental design for a toy, as shown.

WILLIAM F. MAAS.
